UNITED STATES PATENT OFFICE.

JEFF RANKIN, OF GLENDALE, ARIZONA.

SICKLE ATTACHMENT.

1,272,095.

Specification of Letters Patent.

Patented July 9, 1918.

Application filed December 8, 1917. Serial No. 206,252.

To all whom it may concern:

Be it known that I, JEFF RANKIN, a citizen of the United States, residing at Glendale, in the county of Maricopa and State of 5. Arizona, have invented new and useful Improvements in Sickle Attachments, of which the following is a specification.

This invention provides a sickle attachment which is designed to hold the cutting 10 edge of the sickle in constant contact with the ledger plates for the dual purpose of obtaining a shear like cutting action, together with an automatic sharpening of the sickle.

The invention embodies in its make-up a 15 novel construction, combination and arrangement of parts as claimed.

In the drawing forming part of this specification like numerals of reference indicate similar parts in the several views and where- 20 in:

Figure 1 is a top plan view of a sickle and sickle bar showing the component parts of the attachment associated therewith.

Fig. 2 is a vertical transverse sectional view taken on line 2—2 of Fig. 1.

Fig. 3 is a sectional view taken on line 3—3 of Fig. 1.

Fig. 4 is a fragmentary view of one of the cleats and its associated strip.

30 The device forming the subject matter of my invention is susceptible of being used with mowers, reapers and other analogous machines, and as shown in the drawing A indicates a sickle bar and B the sickle which 35 is associated with the sickle bar in the ordinary well known manner.

The attachment embodies a base plate 10 which is adapted to be bolted or otherwise suitably secured to the sickle bar A at an 40 appropriate point in its length. It might here be stated that any number of attachments may be used in conjunction with a single machine, although two will be found sufficient with machines of ordinary construction. Rising from the base 10 adjacent each end is a post 11, the latter being in the nature of a headed bolt passed through the base with the head countersunk in the under side thereof so that the base may be properly 45 seated upon the sickle bar. Reposing upon the base adjacent the rear edge thereof is a cleat or strip 12, while suitably spaced above this cleat, and disposed in parallelism therewith is a similar cleat or strip 13. These 50 cleats have alined apertures through which the bolts 11 pass, while interposed between

the respective cleats 12 and 13 and surrounding the respective bolts 11 are sleeves 14 which maintain the cleats properly spaced apart. Nuts 15 are associated with the free 60 extremities of the bolts 11 and are utilized to maintain the parts hereinabove described fixed relatively.

The cleats 12 and 13 constitute guides for a sliding block 16, the latter being fitted between the cleats or strips 12 and 13, and having its opposite sides grooved or channeled as at 17 to receive the cleats in the manner shown. Projecting forwardly from the block 16 is a rod 18 which has one extremity 65 received within a transverse bore provided in a standard 19 carried by a base 20. A set screw 21 is mounted upon the standard to intersect the bore thereof, and when the set screw is brought into engagement with 70 the rod 18 maintains the standard and rod fixed relatively. As illustrated, the base 20 is bolted or otherwise suitably secured upon the sickle, and the attachment thus provides a connection between the sickle bar and 75 sickle A and B respectively. Encircling the rod 18 is a coil spring 22 having one end bearing against the block 16 and its opposite end bearing against the standard 19. The 80 spring functions to exert pressure upon the standard 19 in a manner so that the cutting edge of the sickle will be effectively maintained in constant contact with the ledger plates, so that as the sickle is reciprocated a shear like cutting action is obtained, while 85 in addition to this fact the cutting edge of the sickle by constant engagement with the ledger plates is automatically sharpened materially increasing the efficiency of the machine for its purpose. The block 16 slides 90 between the cleats or strips 12 and 13 respectively as the sickle is reciprocated, and materially assists in maintaining the sickle properly positioned with respect to the sickle bar to accomplish the above mentioned 95 purposes. It will be noted, that the base 20 may have its position changed upon the sickle to vary the tension of the spring 22 should such be necessary at any time. In 100 other words by loosening the base plate 20 from the sickle, and the set screw 21, the base 20 and standard 19 may be slid upon the bar 18 toward the base 10 to further compress and tension the spring 22, whereupon 105 the set screw 21 is tightened to hold the parts fixed in a given position, and the base subsequently secured to the sickle. It will be 110

further noted that each of the cleats 12 and 13 are provided with a recess 11' for the reception of a lubricant, while secured in any suitable manner to these cleats are strips 5 12' and 13' which constitute closures for the recesses, each of the strips having an opening 14' through which lubricant may be introduced into the recess. One wall of each recess is provided with an opening 15' 10 through which the lubricant escapes from the recess, thus maintaining the associated moving parts of the attachment properly lubricated. The invention is extremely simple in construction and operation, and 15 can be quickly and easily applied to the character of machines with which it is intended to be used.

While it is believed that from the foregoing description the nature and advantages 20 of the invention will be readily apparent, I desire to have it understood that what is herein shown and described is merely illustrative of the preferred embodiment of the invention to which I do not limit myself, 25 and that such changes may be resorted to when desired as fall within the scope of what is claimed.

What is claimed is:—

1. In a machine of the character described, 30 the combination with a finger bar and a reciprocating cutter bar, of a base secured to said finger bar, posts rising from said base, spaced parallel guiding elements fitted on said posts, sleeves surrounding said posts 35 and interposed between said elements to hold the latter spaced, a channeled block arranged to reciprocate between said guiding elements, and a connection between said

block and the cutter bar, and including a spring for maintaining the cutting edge of 40 said bar in constant engagement with the finger bar for the purposes described.

2. In a machine of the character described, the combination with a finger bar, and a reciprocating cutter bar, of a reciprocating block, a support therefor fixed upon the finger bar, a standard secured to the cutter bar, a rod providing a connection between said block and standard whereby the block is reciprocated simultaneously 45 with the movement of said cutter bar, and a coil spring encircling said rod and bearing against said standard to maintain the cutting edge of said cutter bar in constant engagement with the finger bar for the purposes described.

3. In a machine of the character described, the combination with a finger bar, and a reciprocating cutter bar, of a support secured to said cutter bar, a block arranged to slide 60 upon said support, a standard rising from said cutter bar, and having a transverse bore, a rod providing a connection between said block and standard and having one extremity received within said bore, a spring encircling 65 said rod and bearing against said standard to maintain the cutting edge of said bar in constant engagement with the finger bar, said standard being capable of sliding adjustment on said rod to vary the tension of said spring, and a set screw carried by said standard to engage said rod to hold the standard fixed relatively thereto in a given position.

In testimony whereof I affix my signature.
JEFF RANKIN.
